[57] CLAIM

The ornamental design for a display safe, as shown and described.

DESCRIPTION

FIG. 1 is a front elevational view of a display safe showing my new design;

FIG. 2 is a top plan view;

FIG. 3 is a left side elevational view;

FIG. 4 is a rear elevational view;

FIG. 5 is a bottom plan view;

FIG. 6 is a right side elevational view;

FIG. 7 is a right front perspective view, with the outer doors open; and

FIG. 8 is a right front perspective view thereof, with both the inner and outer doors open.
